POLISHING MACHINE FOR POLISHING THE COUPLING LINKS OF SEPARABLE SLIDE FASTENERS

Karl Friedrich Nägele, Stuttgart-Hohenheim, Germany

Application August 25, 1953, Serial No. 376,476

Claims priority, application Germany August 29, 1952

1 Claim. (Cl. 15—21)

The present invention relates to polishing machines, and is particularly directed to a special type of polishing machine provided with rotating brushes for the polishing of, and for the removal of the burr from slide fastening links mounted on the beaded edge of an endless tape or strip, with vacant places, on which no links are mounted, between the individual link sets corresponding in length to the required length of the fastening strips.

Rotating polishing brushes of this kind are already used in fully automatically working machines for the manufacture of slide fastening strips which have their coupling links formed and cut from a metal band and directly secured through clamping to a tape or stringer of textile fabric. Whereby the procedure is such that portions of the tape, corresponding in length to the intended length of the slide fasteners, are provided with links, while the portions between these link-occupied portions which later on form the ends of the slide fasteners, are left without links. The work which the polishing brushes have to perform in a manufacturing process of this kind consists in the removal of the cutting burr from the edges of the links and in the polishing of the rough portions at the lateral edges and at the head portions of the links which are clampingly secured to the beaded edge of the tape.

This work of removal of the cutting burr and of the polishing of the rough portions at the edges of the links is fairly satisfactorily accomplished by the polishing brushes which are now being used. However, these known polishing brushes have the drawback that their steel wires not only act on the links, but also on the portions of the tape which are not provided with links, and thus injure and soil these portions and their beaded edges.

This disadvantage of the known devices is overcome by the machine disclosed in the present invention. According to the invention, the machine is provided with at least two guide members reversing the direction of travel of the fastening strip, and around which the tightened strip is pulled, with the at portions of the links resting snugly against the guide members. On the side facing the appertaining brush each of these guide members is provided with a recess of such width and depth that the links engaging in the recess project from it with at least half the volume of their bodies in such a way that the projecting portions of their bodies are within reach of the brush and can be acted upon by the latter, while the sections of the tightened strip which are not provided with links have their beaded edge portions pulled into the recess to such an extent that they are not within reach of the brush and, therefore, can not be injured or soiled by it. Polishing means of this type can either be directly installed in existing manufacturing machines or operated in cooperation with such machines.

Another disadvantage of the known polishing devices

2

5 resides in the feature that their rotating brushes work the link edges practically only in transverse direction and in such a way that always the same circumferential portions of the brushes are acting on the links, and, for that reason, are prematurely worn off. In order to obviate this drawback, the invention proposes to devise the construction in such a way that the rotating brushes are caused to perform an oscillating movement parallel or substantially parallel to the guide member, so that 10 the link edges are worked in transverse as well as in longitudinal direction, whereby a perfect polishing result and uniform abrasion of the brushes throughout the entire width of their circumference is obtained.

In order to make sure that the links are acted on by the brushes at every portion of their surfaces, it is further advisable to arrange the recesses in the guide members differently from each other in such a way that the surfaces of the links are exposed to the brushes in every recess in a different position.

20 Additional features and advantages of the invention will be understood from a consideration of the following detailed description taken in connection with the accompanying drawings, forming a part of this specification, and in which an embodiment of the invention has
25 been shown by way of illustration. However, I wish to say that the invention is not confined to any strict conformity with the showing of the drawings, but may be changed or modified, so long as such changes or modifications mark no material departure from the salient features of the invention as expressed in the appended claim.
30 In the drawings in which like parts are referred to by the same reference numerals

Fig. 1 is a side elevation of the polishing machine, after removal of a portion of the casing;

35. Fig. 2 is a detail view, partly in section, of a modified form of construction of the supporting and operating means of the polishing brushes:

Figs. 3 and 4 are detail views of the guide members, showing, respectively, how the links and the beaded edge portions of the fastening strip engage in the recesses of the guide members.

Fig. 5 is a detail view, partly in section, showing how oscillation of the brushes may be caused by a rotating cam.

45 Referring now to the drawings in detail, the polishing machine consists of a lower casing 1 in which a driving motor 2 is arranged, and of an upper casing 1a in which two polishing brushes 3 and 4 are rotatably mounted. The polishing brushes 3 and 4 are rotated by the motor 2 in opposite directions. Driven from the motor 2 are further, via an intermediate gearing 5, the conveying means 6 for the fastening strip 7, which in the embodiment illustrated in Fig. 1 consist of a pair of profiled rollers, and a suction fan 8, sucking up the dusty air and forcing it 50 through a filter 9. Positioned between the polishing brushes 3 and 4, for cooperation with the brushes, are the strip reversing guide members 10 and 11. The guide members 10 and 11 are arranged in zigzag fashion above and laterally of each other between the brushes 3 and 4 in 55 such a way that each of the guide members cooperates with one of the brushes. For this purpose, each of the guide members is provided on the side facing the appertaining brush with a recess. The endless tape or stringer 60

7 serving as support for the coupling links (hereinafter called the fastening strip) is pulled through the machine by the conveying means 6. Before reaching the guide members 10 and 11, the fastening strip 7 passes over the braking or tightening means 12, by means of which the fastening strip is constantly maintained in properly tightened condition between the tightening means 12 and the conveying means 6. The tightening means 12 may

be of any suitable kind. After passing the tightening means 12, the fastening strip passes first over the strip reversing member 10 and then over the strip reversing member 11, whereby the coupling links mounted on the beaded edge portion of the strip snugly engage in the recess of the guide members 10 and 11. The guide members may be stationary bolts, or rollers rotatably mounted on stationary bolts. In the embodiment illustrated in the drawings, the bolts 13 are provided with an annular recess 14 in which engage the coupling links 15 clampingly mounted on the beaded edge portion of the strip 16. The depth of the recess 14 should preferably be so selected that it corresponds to approximately half the width or thickness of the coupling links 15, while the width of the recess should correspond to approximately the height or length of the links. From an inspection of Fig. 3 of the drawings it will be seen that, if the guide members are devised like this, one of the lateral edges of the links moves along on the bottom of the recess, while the other lateral edge of the links is within reach of and acted upon by the rotating brushes 3 and 4. On the other hand, if there are no coupling links mounted on portions of the fastening strip, the beaded edge and adjacent portions of the fastening strip engage in the recess to such an extent that the beaded edge and adjacent strip portions are no longer within reach of the polishing brushes and, for that reason, can not be acted upon by the latter. Injuring of the beaded edge and adjacent portions by the thin steel wires of the brushes is therefore reliably prevented (see Fig. 4). The guide members 10 and 11 may be of any suitable kind, and it is, of course, quite possible to devise and arrange the guide members in such a way that the fastening strip with the coupling links mounted on it is brought by the guide members into more extensive contact with the polishing brushes and at different positions or angles with respect thereto.

In order to prevent irregular or nonuniform abrasion of the brushes, and in order to obtain that the lateral edges of the links are acted upon not only in transverse direction, but also in longitudinal direction, the invention contemplates to devise the construction in such a way that the polishing brushes 3 and 4 perform an oscillating movement in axial direction, that is to say, parallel to the direction in which the guide members extend, whereby the depth of the oscillating movement corresponds approximately to the width of the polishing brushes. This oscillating movement, in addition to the rotary movement of the brushes, may be obtained in various ways.

In the embodiment shown in Fig. 1, the oscillating movement is produced through the rotatable arrangement of the polishing brushes 3 and 4 on their supports 17 and 18 and through the rigid arrangement of the supports 17 and 18, on the rotatably supported shaft 19, whereby the supports 17 and 18 should preferably be mounted on the shaft 19 in such a way that shifting of the supports on the shaft after loosening of the adjusting screw 20 is thereby enabled. In an arrangement like this, the polishing brushes can be readjusted without difficulty if the worn-off condition of their circumferential portions makes this necessary. Fastened to the rotatable shaft 19 is further a lever arm 21, having its free end yieldingly urged, for instance by means of a spring 21a, against a cam 21b, driven via a driving wheel 22 from the motor 2. A construction of this kind causes the shaft 19, and the polishing brushes 3 and 4 mounted on the shaft, to perform, during the passage of the fastening strip, the required oscillating movement in axial direction of the guide members 10 and 11.

The oscillating movement of the brushes 3 and 4 can also be produced by an arrangement as illustrated in Fig. 2. In the latter form of construction the polishing brush 30 is merely axially shiftable on a shaft 23, while rotatory adjustment on the shaft is not possible.

The shaft 23 is rotated by the motor 2. Against the hub 30a of the brush 30 bears a compression spring 24 which constantly urges the brush in outward direction against a stop. Coupled to the hub 30a is an arm 25 of a double-armed lever 25, 26 for instance in such a way that the arm 25 constantly engages with a forked end in an annular groove of the hub. The other arm 26 of the lever rests either against a rotating cam, or against a differential drive. In the embodiment illustrated by way of example in Fig. 2, the differential drive consists of two V-belt pulleys 27 and 28 shiftably mounted on a pin 29 and driven at uniform circumferential speed from the motor 2. The pulley 27 rests with its outer hub against the free end of the lever arm 26. The confronting faces of the inner hubs of the two pulleys 27 and 28 are inclined toward the pin 29 (see Fig. 2). Because of their uniform circumferential speed, but different diameters, the two pulleys rotate at different speeds with respect to each other, and thereby cause, owing to the inclination of the confronting faces of their inner hubs, an axial movement of the pulley 27, resulting in an oscillating movement of the double-armed lever 25, 26, whereby the number of the oscillations depends upon the difference in diameter of the two pulleys and upon the circumferential speed.

The polishing machine as hereinbefore described, polishes and removes the burr from one side of the coupling links fastened in the fastening strip 7 by means of the brush 4, and from the other side of the coupling links by means of the brush 3. It prevents with certainty an injuring of the portions of the strip on which no links are fastened, and further prevents nonuniform abrasion of the brushes by means of the oscillating movement performed by the brushes. Owing to the reciprocating movement of the brushes, the links are treated not only in transverse direction, but also in longitudinal direction. If considered necessary, the machine may, of course, be provided with additional pairs of brushes 3 and 4, and appertaining guide members 10 and 11.

The conveying means 6 may be actuated by means of the driving means 5, or with the aid of an infinitely variable change speed gear, so that it is possible to adjust the speed at which the fastening strip is pulled through the machine in conformity with the degree of roughness of the links mounted on the strip.

What I claim as new and desire to secure by Letters Patent of the United States is:

In a machine for polishing slide fastening links mounted in sets on the beaded edge of a strip of indefinite length with vacant places unoccupied by links between the individual sets of links, feeding means and a plurality of strip reversing guide members adapted to continuously feed the strip in zig-zag path with different surfaces of the links alternately engaging the guide members, each of said plurality of guide members being provided with a recess of such width and depth that the links of the strip engaging in the recess project therefrom with approximately half the width of their bodies while the unoccupied beaded edge portions of the strip practically completely engage within the recess; and rotary polishing means for said plurality of guide members and adapted to polish the body portions of the links projecting from the recess of the guide members in longitudinal as well as transverse direction of the strip, said rotary polishing means consisting for each of said plurality of guide members of a brush, and of a support on which said brush is rotatably supported; a shaft on which said supports of the brushes are rigidly and adjustably mounted in such manner that the axis of every brush extends parallel to the axis of the appertaining guide member; and rocking means connected with said shaft and adapted to rock said shaft to thereby cause said brushes to perform an oscillating movement sub-

stantially parallel to the axis of the appertaining guide member and corresponding in range to the width of said brush, said rocking means consisting of a rotating cam, a rocker arm having one end rigidly secured to said shaft, and a spring adapted to yieldingly urge the free end of said rocker arm against said rotating cam to receive rocking motion therefrom.
